ABSTRACT

An induction disc type relay adapted to apply to an induction disc a rotational torque proportional to an input so that an operating output is produced at the expiration of a predetermined time dependent on the magnitude of the input after the application of the input. Included in the relay are two sets of shading coils and reluctance paths responsive to the same input signal for applying the rotation torque to the induction disc, whereby a desired time lag characteristic can be readily obtained.

INDUCTION DISC TYPE RELAY

BACKGROUND OF THE INVENTION

1. Field of the Invention

The present invention relates to induction disc type relays.

2. Description of the Prior Art

An induction disc type relay is generally used as time lag relay which requires a predetermined time between the application of an input thereto and the generation of its operating output.

In FIG. 1, there is shown the operating characteristic of a time lag overcurrent relay which is the most frequently used application of the induction disc type relay as a time lag relay and in this figure the abscissa represents the input current (in terms of multiples of the set operating value) and the ordinate represents the operating current (in seconds), while curves (A), (B) and (C) represent what are usually termed an operating time lag characteristics.

While there has been formed no clear definition of each of the curves (A), (B) and (C), the curve (A) is generally defined as an inverse and definite time lag characteristic showing that the operating time becomes shorter as the input current increases, but the operating time becomes practically constant with the input current exceeding about ten times the value of the set operating value, while the curve (C) is called as a very inverse time lag characteristic showing that the operating time becomes rapidly shorter in inverse proportion to the input current. On the other hand, the curve (B) is called an inverse time lag characteristic which is almost intermediate between the characteristic of the curve (A) and that of the curve (C). Although not shown in FIG. 1, a characteristic showing the operating time whose rate of change with the input current is more rapid than is the case with the characteristic curve (C) is termed an extremely inverse time lag characteristic, while a characteristic which comes practically between those of the curves (A) and (B) is called a moderate inverse time lag characteristic.

It is well known in the art that these time lag characteristics may be suitably selected according to the kinds of apparatus to which overcurrent protection must be afforded, and fault conditions etc.

In order that the operating time lag characteristic may be changed to suit any input current, it is necessary to vary the driving torque provided to an induction disc. For example, the characteristic (A) may be obtained if it is so arranged that the driving torque will become constant with a current value exceeding 10 times the operating value, while the characteristic (C) may be obtained if it is so arranged that the driving torque remains on the increase so far as the input current is within the illustrated range. The induction disc type relays which are now in practical use may be divided into two broad classes according to the kinds of driving electromagnets used, that is, a transformer (split phase) type relay as shown in FIG. 2 and a shading coil type relay as shown in FIG. 3.

These two types of relays will now be briefly described. Firstly, the transformer type relay shown in FIG. 2 includes a core 1 provided with a main pole 2 and magnetic poles 3 formed thereon, and a primary coil 4 to which an input is applied and a secondary coil 5 are both wound on the main pole 2 with one end of the secondary coil 5 being wound on a saturable transformer 6. One end of another coil wound on the saturable transformer 6 is connected to a magnetic pole coil 7 wound on the magnetic poles 3. Numeral 8 designates an induction disc rotatably disposed in an air gap between the main pole 2 and the magnetic poles 3.

With the construction described above, it is so arranged that the magnetic path of the primary coil 4 is readily saturable and at the same time the magnetic pole coil 7 is excited by the secondary saturation current of the saturable transformer 6 to saturate the driving torque on the induction disc 8.

Therefore, while the transformer type relay is well suited to obtain an inverse and definite time lag characteristic such as the characteristic (A), it has a drawback in practical use in

that the construction is complicated compared to the shading coil type relay, that the operation of winding the primary coil 4 and the magnetic pole coil 7 is a difficult undertaking and hence the working efficiency is low, and that the apparent power consumption in terms of volt-amperes is high.

On the other hand, as shown in FIG. 3, the driving electromagnet portion of the shading coil type relay includes a core 9 on which is wound an exciting coil 10 to which an input is applied, and the air gap portions of the core 9 are formed 10 into the shape of forks by means of a slot 11 so that a shading coil 12 is wound on one of the respective forked poles. An induction disc 13 is also disposed in the air gap formed by the core 9 so that the induction disc 13 rotates about a shaft 14 within the air gap.

Then, as an input is applied to the exciting coil 10 and the disc 13 is rotated by the shifting magnetic field, an operating output is produced when the disc 13 rotates through a predetermined angle, that is, an operating output is delivered at a specified time after the application of the input.

In this manner, the shading coil type relay performs the time lag action thereof, and its advantages include a very simple construction which can be completed by simply mounting the shading coils and hence good working ability and a low apparent power consumption (volt-ampere) as compared with the transformer type relay are obtained.

However, since the shading coil type relay has a relatively large air gap portion in the magnetic circuit thereof, it is difficult to obtain a definite time lag characteristic, even if a core 30 material is used which exhibits an almost rectangular hysteresis characteristic, and so the shading coil type relay is suited for applications where it is desired to obtain such an operating time characteristics as the characteristics (B) and (C).

The experiments conducted by the inventors have shown 35 that a definite time lag characteristic satisfactory for the most part could be obtained if a 78 percent Permalloy (nickel content, 78 percent) having an almost rectangular hysteresis characteristic (i.e., the saturation density is constant) were used as a core material, but Permalloy is very expensive and 40 has the drawback of increasing the cost of a relay incorporating it.

SUMMARY OF THE INVENTION

45 The present invention aims at eliminating the deficiencies described above and therefore one object of the present invention is to provide an induction disc type relay of a shading coil type which is capable of easily obtaining not only an inverse time lag characteristic, but also an inverse and definite time lag characteristic.

Another object of the present invention is to provide an induction disc type relay which is very simple in construction and low in power consumption (volt-ampere).

55 A further object of the present invention is to provide an induction disc type relay which is inexpensive and capable of achieving the expected effects without using any special and expensive material as the core material.

Those and other objects and features of the present invention will be readily apparent from the following descriptions of the preferred embodiments taken in conjunction with the accompanying drawings.

BRIEF DESCRIPTION OF THE DRAWING

65 FIG. 1 is a diagram showing the time lag characteristic of a time lag overcurrent relay which is the most typical of the applications of induction disc type relays;

FIG. 2 is a schematic diagram showing the driving section of a transformer type relay;

FIG. 3 is a schematic diagram showing the driving section of a prior art induction disc type relay;

FIG. 4 is a schematic diagram showing the principal part of an embodiment of the present invention;

FIG. 5 is a plan view schematically showing the induction disc used in the device of FIG. 4;

FIG. 6 is a diagram for explaining the operation of the device of the present invention; and

FIG. 7 is a schematic diagram showing the principal part of another embodiment of the present invention.

DESCRIPTION OF THE PREFERRED EMBODIMENTS

FIG. 4 illustrates diagrammatically the driving section of an induction disc type relay according to the present invention. In the figure, numeral 15 designates an exciting coil wound on a core 16, 17 a rotary disc which rotates about a shaft 18 within air gaps, g_1 and g_2 as shown in FIG. 5, thereby closing the contacts which are not shown. The magnetic pole portions where the magnetic flux in the core 16 interlinks the disc 17 are divided into pairs of magnetic poles 19, 19' and 20, 20' and each of these poles 19, 19' and 20, 20' is in turn forked so that shading coils 21, 21', 22 and 22' are mounted at the respective positions of the forked poles. These shading coils 21, 21', 22 and 22' are positioned as shown in the figure so that torques produced at the respective shading coils tend to oppose each other. Numeral 23 designates a restraining spring having one end connected to the shaft 18 and the other end to some relay member so that when the disc 17 rotates in the normal direction of movement thereof, the spring 23 produces a definite restraining torque in the direction opposite to the direction of movement of the disc 17.

Although not shown in the figure, a permanent magnet (braking magnet) is separately provided to retard the motion of the induction disc 17 so as to give a time lag as with those induction disc type relays which are now in practical use.

With the construction described above, when an input is applied to the exciting coil 15, the magnetic flux produced in the magnetic poles 19, 19' interlinks or passes through the disc 17 to rotate it clockwise, thereby producing an operating torque in the direction to close the relay contacts. On the other hand, the magnetic flux produced in the magnetic poles 20, 20' rotates the disc 17 counter-clockwise to produce a restraining torque in the direction to restrain the closing of the contacts. As a result, the disc 17 will be driven by the difference between the torque produced by the poles 19, 19' and that by the poles 20, 20'.

Now consider the construction of the magnetic circuit comprising the core 16 as the principal part thereof and the magnetic reluctance of the magnetic path between points A and B on the core including the pole air gaps. The air gap g_1 of the magnetic path including the poles 19, 19' may be selected to be smaller than the air gap g_2 of the magnetic path including the poles 20, 20' so that the reluctance of the former will remain smaller than that of the latter until the magnetic path between the points A and B become saturated, while the cross-section of the poles 19, 19' may be made smaller than that of the poles 20, 20' so that this portion will become saturated first.

With the magnetic paths arranged as described above, the relationships between the excitation ampere-turns of the exciting coil 15 and the magnetic flux in each of the magnetic poles are as shown in FIG. 6.

In FIG. 6, ϕ_1 designates the magnetic flux passing 6, the poles 19, 19'; ϕ_2 the magnetic flux passing through the poles 20, 20'; T_1 and T_2 torques produced by the magnetic fluxes ϕ_1 and ϕ_2 , respectively. Now, if the constants of the torques T_1 and T_2 are K_1 and K_2 , respectively, these torques T_1 and T_2 are given by the following equations:

$$T_1 = K_1 \phi_1^2 \text{ (clockwise)} \quad (1)$$

$$T_2 = K_2 \phi_2^2 \text{ (counterclockwise)} \quad (2)$$

Then, a torque T_3 for driving the disc 17 is given by

$$T_3 = T_1 - T_2 \quad (3)$$

If the restraining torque as produced by the restraining spring 23 is T , then the composite torque T which is to be applied to the disc 17 is given by

$$T = T_3 - T \quad (4)$$

Thus, if the result is positive, the disc 17 will be rotated to close the contacts.

Assuming now that the magnetic flux ϕ_1 remains to be proportional to the excitation ampere-turns of the coil 15 after it has reached the saturation magnetic flux ϕ_s , while the magnetic flux ϕ_2 will not be saturated, but it remains to be proportional to the excitation ampere-turns of the exciting coil 15, then the following equations result:

$$\phi_1 = \phi_s + K_3 NI \quad (5)$$

$$\phi_2 = K_4 NI \quad (6)$$

Where

10 N = the number of turns of the exciting coil 15

I = current

K_3 and K_4 = constants

15 Substituting the above equations (5) and (6) into the equations (1) and (2), the torques T_1 and T_2 are given by the following equations:

$$T_1 = K_1 \phi_s + K_3 N(I - I_s)^2 - K_2 (K_4 NI)^2 \quad (7)$$

$$T_2 = K_2 (K_4 NI)^2 \quad (8)$$

where I_s = the saturation current of the poles 19, 19'. Thus, the composite torque T is given by

$$20 T = K_1 \{\phi_s + K_3 N(I - I_s)^2 - K_2 (K_4 NI)^2\} - K_1 \phi_s^2 + [2K_1 K_3 \phi_s N(I - I_s) + K_1 \{K_3 N(I - I_s)^2 - K_2 (K_4 NI)^2\}] - T_0 \quad (9)$$

25 Considering the constants put in the bracket in the second member on the right side of the equation (9), K_4 may be varied by means of the reluctance of the magnetic path including the poles 20, 20', i.e., the air gap g_2 , the cross-section of the magnetic poles etc., while K_2 may be varied by means of the shading coils 22, 22'. In other words, the constant K_2 will be zero in the absence of the shading coils 22, 22'.

30 Then, if the value of the bracketed second member on the right side of the equation (9) is reduced to zero within the range of the input current shown in FIG. 1, the combined torque T can be made constant independent of the excitation ampere-turns of the exciting coil 15, i.e., the input current and hence the operating time can necessarily be made constant, thereby giving a definite time lag characteristic.

35 40 However, as will be seen from the equation (9) and FIG. 6, the value of the bracketed second member on the right side of the equation (9) can not be reduced to zero, whereas if, for example, the constant K_2 of the restraining torque T_2 is changed to K'_2 and the value of this constant K'_2 is so chosen that the operating torque T_1 and a restraining torque T'_2 increase at the same rate, the value of this bracketed member can be almost reduced to zero so that the combined torque T can remain constant with respect to the input after a certain point has been reached.

50 55 On the other hand, if it is so chosen that the ampere-turns required for the magnetic flux ϕ_1 to become equal to the saturation magnetic flux ϕ_s are obtained at a near point a of the curve (A) in FIG. 1, that is, with a current of about ten times the set operating value, the time lag characteristic of such a relay can take the form of an inverse and definite time lag characteristic as shown by the curve (A) in FIG. 1.

Furthermore, if the constants K_2 and K_4 are so chosen that the restraining torque T_2 in the counter-clockwise direction becomes smaller, the combined torque T will increase as the excitation ampere-turns of the exciting coil 15 increase, so that the operating time becomes gradually shorter as the input increases to approach the characteristics shown at (B) and (C) in FIG. 1, thereby giving an inverse time lag characteristic and a very inverse time lag characteristic.

60 65 70 75 It is now evident from the foregoing that according to the present invention a core adapted to be energized by an exciting coil is formed with two pairs of magnetic poles for producing an operating torque and a restraining torque, respectively, so that any desired time lag characteristics ranging from an inverse and definite time lag characteristic to a very inverse time lag characteristic can be obtained with varying values of the restraining torque which may be accomplished by changing the related constants by means of the air gaps and the cross-section of the poles which produce the restraining torque.

Thus, one of the very important features of the present invention resides in that an inverse and definite time lag characteristic which has been considered as hardly attainable with conventional relays, particularly the induction disc type relays, is now obtainable with extreme easiness according to the present invention.

While the magnetic poles for producing the operating torque and the restraining torque are formed on the same core in the embodiment shown in FIG. 4, another embodiment of the present invention in which such magnetic poles are formed on different cores will now be explained with reference to FIG. 7.

In FIG. 7, numerals 23 and 24 designate electromagnets for producing an operating torque and a restraining torque, respectively, and the electromagnet 23 comprises a core 27 which is provided with magnetic poles 26, 26' with shading coils 25, 25' and on which is wound an exciting coil 28 to which an input is applied, whereby the operating torque in the direction of an arrow 30 is produced on an induction disc 29 rotatably disposed between the magnetic poles 26, 26'. The electromagnet 24 similarly comprises a core 33 which is provided with magnetic poles 32, 32' with shading coils 31, 31' and on which is wound an exciting coil 34 to which the same input as with the electromagnet 23 is applied, so that a restraining torque in the direction of an arrow 35 which is opposite to the direction of the operating torque produced by the electromagnet 23, is produced on the disc 29 or some other disc which is mechanically coupled to the disc 29. Thus, the same effects as obtained with the embodiment of FIG. 4 can be achieved by suitably selecting the value of the constant of the electromagnet 24, such as by varying the air gap of core 33 with respect to core 27 of electromagnet 23.

As described hereinbefore, according to the present invention means are provided to produce both an operating torque and a restraining torque, i.e., a rotational torque on an induction disc, whereby the means for applying the restraining torque may be controlled to suitably select and regulate the restraining torque so as to obtain any desired characteristics including not only an inverse time lag characteristic and a very inverse time lag characteristic, but also an inverse and definite time lag characteristic.

Furthermore, since an inverse and definite time lag characteristic which has hitherto been obtainable only with transformer type relays can be obtained with induction disc type relays, such an inverse and definite time lag characteristic is now attainable with relays which are low in the apparent power consumption (volt-amperes), easy to manufacture and superior in economy. Moreover, any good time lag characteristic can be obtained with inexpensive relays, since such a good characteristic is obtainable without using specific and expensive alloys such as Permalloy but using inexpensive material such as silicon steel as a core material.

While the present invention has been described with

reference to the particular embodiments of the invention, it should be apparent to those skilled in the art that many other embodiments can be conceived without departing from the scope of the spirit of the present invention.

We claim:

1. In an induction disc type relay including an induction disc and means for applying a rotational torque to said disc, the improvement wherein said means for applying a rotational torque to said disc comprises:

first means, responsive to an input signal, for supplying a first operating torque to rotate said disc in a first direction; and

second means, responsive to said input signal to which said first means is responsive, for supplying a second operating torque to rotate said disc in a direction opposite to said first direction,

wherein said first and second means each comprises a shading coil magnetic pole structure having differently spaced air gaps mounted on the single core piece, whereby, the resultant torque applied to rotate said disc results from the application of the same input signal to said first and second means, so that a desired inverse time lag characteristic can be accurately obtained.

2. An induction disc type relay according to claim 1,

25 wherein said disc is mounted on a shaft having a bias spring provided therefor to impart a bias torque to said disc in one of said directions.

3. An induction disc type relay according to claim 2, including a singular input coil mounted on said core structure to which said input signal is applied.

4. An induction disc type relay including an induction disc and means for applying a rotational torque to said disc, the improvement wherein said means for applying a rotational torque to said disc comprises:

first means, responsive to an input signal, for supplying a first operating torque to rotate said disc in a first direction; and

second means, responsive to said input signal to which said first means is responsive, for supplying a second operating torque to rotate said disc in a direction opposite to said first direction,

wherein said first and second means each comprises a shading coil magnetic pole structure having differently spaced air gaps mounted on separate core pieces and including a pair of input coils mounted on said pieces and having the inputs thereof each receiving said input signal so that said input signal will be applied to each of said core pieces and, thereby, to said shading coil magnetic pole structure, whereby, the resultant torque applied to rotate said disc results from the application of the same input signal to said first and second means, so that a desired inverse time lag characteristic can be accurately obtained.
